United States Patent

Des. 240,566
Patented July 13, 1976

240,566

CARRYING HARNESS

Ingvar Westerberg, Vretvagen 39,
S-352 47 Vaxjo, Sweden

Filed Oct. 9, 1974, Ser. No. 513,496

Term of patent 14 years

Int. Cl. D3—99

U.S. Cl. D87—1 R

The figure is a perspective view of a carrying harness showing my new design, the rear side of the suspended plate, not shown, is substantially plain and unornamented.

I claim:

The ornamental design for a carrying harness, as shown and described.
